UNITED STATES PATENT OFFICE.

LOUIS A. EGAV, OF CHICAGO, ILLINOIS, ASSIGNOR OF FORTY ONE-HUNDREDTHS TO
MELCON A. KARAIAN, OF WEEHAWKEN, NEW JERSEY.

HAT-FASTENER.

1,246,071.

Specification of Letters Patent. Patented Nov. 13, 1917.

Application filed March 9, 1915. Serial No. 13,112.

To all whom it may concern:

Be it known that I, LOUIS A. EGAV, a citizen of Russia, and a resident of the city of Chicago, in the county of Cook and State of Illinois, have invented certain new and useful Improvements in Hat-Fasteners, of which the following is a specification.

The invention relates to means for retaining women's hats and headwear generally in the desired position upon the head of the wearer; and the object of the invention is the production of means for this purpose which will retain the hat or other headwear in position with a minimum disarrangement of the hair and a minimum destruction of the hat or other headwear; a further object of the invention is the elimination of the danger and annoyance caused by the sharp points of the hat pins now commonly employed; a further object of the invention is the production of such fastening means at a reasonable cost of the mechanical parts but which can be made as ornamental as may be desired.

The broad feature of the invention comprises the employment of one or more curved pins to which is attached a means by which said pin or pins can be turned through the hair of the user so as to engage the hair, without disarrangement thereof or injury thereto or to the scalp, and in this manner retain the hat or other headwear in its desired position upon the head; and by which the said pin or pins can be turned out of engagement with the hair, without disarrangement thereof, when it is desired to remove the hat or other headwear from the head.

As a specific presentation of the invention, I have illustrated one embodiment thereof in the drawings which form a part of this application and in which—

Figure 1 is a perspective view of my invention partly broken away showing the parts in a position ready for use;

Fig. 2 is a sectional view of my invention generally vertical in character illustrating in part a section through the center and in part a section in the line of movement of one of the holding pins of this form of my invention, the holding pins themselves being shown in elevation; and the parts being in their holding or retaining position; and

Fig. 3 is a vertical section of a detail of the form illustrated taken through the center of Fig. 1.

In the form illustrated two holding or retaining pins 1, 1, are firmly fastened in either end of a bar 2, to which is attached centrally an upright pin 3 provided at its top with a button 4 rigidly attached thereto but readily removable therefrom. The holding pins are preferably of a resilient material and helical in configuration.

When in a position ready for use the holding pins and the bar are retained in a shallow casing comprising a box portion 5 and a cover 6 therefor each conveniently but not necessarily made of metal. The box portion has near its periphery and on opposite sides guides 7, 7, within which the respective holding pins are turned; and apertures 8, 8, located a short distance beyond the guides through which the holding pins pass when turned into their holding position (see Fig. 2).

When the box portion of the casing is made of metal these guides and apertures can conveniently be made by pressing or stamping, and the apertures located in a general vertical position with their upper surface sloping in the curvature of the holding pins. Obviously the same construction could readily be effected or its equivalent produced if other materials were employed. The center of the box portion of the disk is provided with a suitable bearing such as a truncated cone 9, for retaining the bar 2 in its proper position and about and upon which the bar rotates, the bar being suitably hollowed out for this purpose. The bar can be provided with wings 11, 11, of a thickness approximately equal to the depth of the casing, to expedite the turning of the bar in the casing and prevent jamming thereof.

A stop 12 is provided and so positioned that when the bar is turned in the direction, here shown as clockwise, to withdraw the holding pins from the hair into the casing the movement of the bar will be arrested after the ends of the holding pins have been drawn through the apertures 8, 8, but before they have passed through the guides 7, 7. The guides themselves serve as stops for the bar when turned to move the holding pins into engagement with the hair and prevent the holding pins from jamming in the apertures 8, 8. The cover of the casing is preferably provided with convenient means for attachment to the inside of the

hat or other headwear. I have illustrated eyes 13, 13 and points 14, 14, for this purpose.

The upright pin 3 extends through a central aperture 15 in the cover of the casing. It is here shown as fastened to the bar 2 by having its lower end first bent at right angles and extending through a channel 16 in the bar, and then being clenched.

10 I have illustrated the button 4 as attached to the pin by providing the button with a central vertical channel 17 of the same diameter as the upright pin and into which the pin is placed. The lower part of the 15 channel is cut away at one side as at 18 and provided with a leaf spring 19. The upright pin is made with a tooth 20 beveled on its upper surface and having its lower surface at right angles with the axis of the 20 pin. The spring 19 engages the lower face of the tooth 20 and prevents the button from being unintentionally withdrawn from the pin; and the tooth engages the cut away portion 18, and prevents the button from 25 turning on the pin. The button may be of any ornamental character desired.

In the use and operation of this fastening means one or more fasteners are suitably attached to the inside of the hat or other headwear in a position so that the holding pins can most effectively grip the hair, without disarrangement thereof or discomfort to the user, attention being paid to the character of the hat or other headwear itself, and the 30 button having been first removed so that the upright pin can pierce the hat or other headwear and project therethrough to the outside. The buttons are then attached to the 35 ends of the upright pins as above described and the holding pins turned into position 40 and the holding pins turned into position ready for use if not already in that position. When the hat or other headwear is adjusted on the head the buttons are turned counter-

clockwise and cause the holding pins to pass through the apertures 8, 8, and engage the 45 hair. If desired the turning movement can be continued until the holding pins assume the position of Fig. 2. When it is desired to remove the hat or other headwear the buttons are turned in a clockwise direction until 50 the holding pins again assume the position of Fig. 1, and the hat or other headwear can be removed without interference.

Obviously if it is not desired that the upright pins or buttons appear on the outside 55 of the hat or other headwear they can be hidden from view if the trimming or character of the hat permits. Furthermore the casing can be ornamented if desired to harmonize or contrast with the hat or other 60 headwear and may be attached to the exterior thereof.

The foregoing detailed description has been given for clearness of understanding and no undue limitations should be deduced 65 therefrom, but the appended claim should be construed as broadly as permissible in view of the prior art.

What I claim as new and desire to secure by Letters Patent of the United States, is— 70

In a hat fastener the combination of a plurality of helical holding pins, an upright pin connected therewith, a removable button rigidly attached to the upright pin, and a closed casing in which the holding 75 pins are mounted and which retains the holding pins when not in holding position, the casing being provided with apertures through which the holding pins may be projected and withdrawn by turning the button 80 and means for guiding the holding pins into said apertures, substantially as described.

LOUIS A. EGAV.
